US0D1068851S

(12) **United States Design Patent** (10) **Patent No.:** **US D1,068,851 S**
(45) **Date of Patent:** **** Apr. 1, 2025**

(54) **DISPLAY SCREEN WITH A GRAPHICAL
USER INTERFACE**

(71) Applicant: **Sanofi (China) Investment Co., Ltd.**,
Shanghai (CN)

(72) Inventor: **Dong Wang**, Paris (FR)

(73) Assignee: **Sanofi (China) Investment Co., Ltd.**,
Shanghai (CN)

(**) Term: **15 Years**

(21) Appl. No.: **29/914,893**

(22) Filed: **Oct. 23, 2023**

(30) **Foreign Application Priority Data**

Apr. 24, 2023 (CN) 202330233210.5

(51) **LOC (15) Cl.** **14-04**

(57) **CLAIM**

The ornamental design for a display screen with a graphical user interface, as shown and described.

DESCRIPTION

The FIGURE is a front view of a display screen with a graphical user interface showing my new design.

The broken line showing of the display screen and portions of the graphical user interface are included for the purpose of illustrating environmental structure and portions of the article. The broken lines form no part of the claimed design.

1 Claim, 1 Drawing Sheet
